LUGGAGE HANDLE

Jerome W. Epton, Chicago, Ill., assignor to National Leather Handle Co., Inc., Chicago, Ill., a corporation of Illinois

Application June 21, 1952, Serial No. 294,818

1 Claim. (Cl. 190—57)

1

This invention relates to certain new and useful improvements in luggage handles.

A principal object of the invention is the provision of a luggage handle of the character hereinafter described which may be constructed at an economical cost and one which will be substantially durable in use.

Another and equally important object of the invention is to provide a luggage handle comprising relatively few parts and which requires relatively simple operations in assembly.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a plan view of a blank from which my improved luggage handle is formed;

Fig. 2 is a side elevational view of the completed luggage handle;

Fig. 3 is an end elevational view of the same; and

Fig. 4 is a sectional detail view taken substantially on line 4—4 of Fig. 2.

The several objects of my invention are accomplished by the preferred form of construction shown in the accompanying drawings and which construction comprises a handle 10. This handle 10 is formed from a blank of material 11 providing two oppositely arranged handle sections 12 each substantially channel-shaped in cross section. These handle sections 12 are integrally joined together by web portions 13. The blank is folded centrally upon itself to dispose the handle sections 12 in juxtaposition with respect to each other, thereby to form the completed handle. Prior to the formation of the handle by the folding of the handle sections 11 and 12 in the manner above stated, the luggage connecting links 14 are journaled upon the web portions 13 so that when the handle sections 12 are disposed as shown in Fig. 2, the web portions 13 provide bearings for these connecting links 14. The abutting edges 15 of the handle sections are secured together by spot welding or the like, such for example, as shown at 16.

These spots of welding are dressed down so that there will be no protuberances from the surface of the handle 10.

To complete the invention, the outer surfaces

2

of the handle sections 12 are covered with a relatively thin covering of plastic material 17 which may be various colors to match the luggage with which the handle 10 is associated.

From the foregoing description it is clear that I provide a luggage handle which is relatively simple in construction, comprising relatively few parts, thus affording economical assembly without minimizing the durability of the handle.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

A luggage handle comprising a blank of material providing oppositely disposed handle sections each substantially channel-shaped in cross section, said handle sections being substantially U-shaped and having adjacent end portions integrally connected together by notched out web portions, said web portions being folded together to dispose the handle sections in juxtaposition with respect to each other with their edges arranged in abutment, and having the notched out portion forming bearings for pivotally receiving before being folded together connecting links for attachment to said luggage, a welding securing the abutting edges together, said welding being flush with the adjacent outer surface of the handle sections at their abutting edges, and a plastic covering over the outer surfaces of said handle sections.

JEROME W. EPTON.
